UNITED STATES PATENT OFFICE.

OCTAVE P. HOWARD, OF ROCKLAND, MAINE.

BUSH-HAMMER.

SPECIFICATION forming part of Letters Patent No. 430,649, dated June 24, 1890.

Application filed January 22, 1890. Serial No. 337,775. (No model.)

To all whom it may concern:

Be it known that I, OCTAVE P. HOWARD, residing at Rockland, in the county of Knox and State of Maine, have invented a new and 5 Improved Bush-Hammer, of which the following is a specification.

My invention relates to improvements in bush-hammers; and the objects of my improvements are, first, to secure a gib or bearing for the cuts or knives a part of and as solid as the pole itself, it being a part of the pole. The essential feature of a bush-hammer is to have the pole hold the cuts or knives so rigidly as to cause the hammer to rebound when 15 struck on the granite or stone. The moment the cuts become loose or move in the slightest degree the hammer is called a "loose hammer," and is tiresome to work and does imperfect work; second, to secure the heads or 20 side flanges of the gib as a part of and as solid as the pole itself, to prevent any lateral movement of the cuts; third, to lock the two sides of the pole of a bush-hammer by a dovetail mortise, so as to prevent any longitudinal 25 movement of the sides; fourth, to secure a pole for a bush-hammer, composed of only two parts, each being the duplicate of the other, and the same mold will cast or form either side; fifth, to secure a bush-hammer in 30 which the gib or anvil receives severest and continued pounding on its strongest part; sixth, a bush-hammer whose jaws can be opened, and cuts of varying thickness used in the jaws, so that same bush-hammer pole 35 can be used for a heavy or light hammer by opening it for heavy cuts and coarse work, or by closing the jaws for light cuts; also made into a scotia hammer by closing the jaws as close as may be necessary; seventh, a bush- 40 hammer whose eye can be made in halves, and can thus be cast, and avoid the expense of boring a round or oblong hole in the pole; eighth, a bush-hammer pole in which the eye, when made larger or smaller by opening the 45 sides of the pole to receive different or more numerous cuts, still retains a bearing-surface on the entire circumference of the handle, the larger or smaller hole being filled by driving the handle into the eye to a greater or lesser extent. I attain these objects by the mechanism illustrated in the following drawings, 50 in which—

Figure 1 is a perspective view of the whole hammer. Fig. 2 is a perspective view of one half of the pole. Fig. 3 is a perspective view 55 of the other half of the pole.

Similar letters refer to similar parts throughout the several views.

A B C is the pole made solid of two parts— duplicates of each other, except that one may 60 be called the right and the other the left as they fit together.

a b c is the gib or anvil with its two heads; a b a b, the heads of the gib, used to prevent any lateral movement of the cuts or knives; 65 D E, the cuts or knives; F G, the shoulder on which one end of the gib or anvil rests; s s s, each one-half the eye of the hammer or hole to receive the handle; x x x x, holes for the screw-bolts or set-screws of the hammer; e d, 70 a mortise on the sides of the jaw of hammer to receive part of the gib or anvil.

k l m indicate a portion cut out of the plate on each side, making a wedge-shaped recess to admit the projecting heads of the gib, and 75 which together form a dovetail mortise or fastening.

When the hammer is set up or put together, the projecting heads of the gib a b of one half lock its opposite half, and the projecting 8c heads of the opposite half lock the first half, and the side projection of each half locks the cuts D E laterally. These heads of the gib also, by means of the dovetail mortise k l m, 85 lock the two sides of the pole, so as to prevent any longitudinal movement. The mortise e d in one side of the jaw of the pole admits the end of the gib of the opposite side, and by this means renders it possible to open or close the jaws of the pole to the extent of 90² the depth of the mortise.

The opening and closing of the two sides of the pole will vary the size of the eye of the pole; but this is met by driving the handle into the eye to a greater or lesser extent, as 95 may be necessary.

Another advantage is obtained by the mortise—viz., the shoulder F G is by it made wide and affords a more solid bearing for the anvil or gib a b c. The gib a b c, being a part of the pole 100 itself, is rigid and cannot become loose or move in any way to make the hammer a loose hammer, but will preserve the rebound of the clip essential to easy and good work. C, the anvil

on which the cuts rest, or the gib, is solid on one side of the pole. The anvil of the other end of the pole is solid on the opposite side. The advantage of this is that when the hammer is used involuntarily the edge of the hammer toward the right hand strikes the stone first, and hence the right sides of the cuts receive most of the force of the blow, and this extra force is received on that part of the anvil nearest the side to which it is united solidly. When the other end of the hammer is used, the same result is obtained.

The hammer can be used as a left-hand hammer by inserting the handle in the opposite side.

The bolts $x x x x$ are used to set the jaws of the pole firmly against the cuts.

I am aware that prior to my invention bush-hammer poles have been made from one piece 20 with a spring or slight attainable movement of the jaws; also made in two parts with a gib or rigid bearing at the bottom of the cuts. I therefore do not claim such combinations, broadly; but

25 What I do claim as my invention, and desire to secure by Letters Patent, is—

1. A bush-hammer pole formed of two interlocking duplicate halves having a mortise

or notch $e d$ in their sides just below their jaws and between the jaw and the eye, with 30 an interlocking gib $a b c$, and interlocking heads $a b$ of the same gib, the jaws of which pole may be made larger or smaller to accommodate different-sized cuts, and having a wedge-shaped mortise $k l m$, so as to make it 35 dovetailed in form to fit a corresponding part $a b$ of the opposite half of the pole, all substantially as set forth.

2. A bush-hammer pole, in which the projecting heads of a gib, the same being a part 40 of the pole itself, in combination with the wedge-shaped recess $k l m$, make a dovetailed mortise, which locks the opposite sides of the pole of the hammer longitudinally, substantially as described.

3. The combination, in a bush-hammer, of the projecting head of gib, of one of the sections provided with the dovetailed mortise $f g$, with the dovetail interlocking plate $e d$ of the other section, all substantially as and 45 for the purposes set forth.

OCTAVE P. HOWARD.
